Fig. 8.

Fig. 9.

Fig. 10.

FIG. 1 is a front elevational view of a regulator console panel for aircraft breathing equipment or the like, showing our new design;

FIG. 2 is a side elevational view thereof;

FIG. 3 is an end elevational view thereof;

FIG. 4 is an opposite end elevational view thereof;

FIG. 5 is a fragmentary sectional view thereof taken about on line 5—5 of FIG. 1;

FIG. 6 is a front elevation of a modified embodiment of the regulator console panel disclosed in FIG. 1;

FIG. 7 is a side elevational view thereof;

FIG. 8 is an end elevational view thereof;

FIG. 9 is an opposite end elevational view thereof; and

FIG. 10 is a fragmentary sectional view thereof, taken about on line 10—10 of FIG. 6.

The sides not shown are mirror images of the sides shown in FIGS. 2 and 7, respectively.

The dominant features of our design resides in the portions shown in full lines.

This is a continuation-in-part of design application Ser. No. D. 79,181, filed March 25, 1964, and now abandoned.

We claim:

The ornamental design for a regulator console panel for aircraft breathing equipment or the like, substantially as shown and described.
